Original application Aug. 24, 1964, Ser. No. 391,529, now
Patent No. 3,333,282. Divided and this application Feb.
24, 1967, Ser. No. 618,500

15 Claims. (Cl. 206—65)

ABSTRACT OF THE DISCLOSURE

An assembly of one or more laundry tubs and a plurality of supporting legs arranged for shipment with the legs for a tub extending across the undersurface of its bottom wall and being held in place adjacent structure projecting from the bottom wall. A plurality of tubs are nested one within another and each nested tub may be maintained out of contact with the bottoms of adjacent tubs.

Cross-reference to related application

This application is a division of my copending application, Ser. No. 391,529, filed Aug. 24, 1964, and entitled, "Utility Tubs," now Patent No. 3,333,282.

Background of the invention

This invention relates generally to utility tub constructions, and more specifically to a new molded plastic utility tub and to an arrangement of a plurality of such tubs for packaging and shipping purposes.

A typical single laundry tub is supported by a plurality of legs when in use. In one conventional assembly, the legs are attached to a separately fabricated metal base which engages the bottom wall of the tub. In another known arrangement, the legs have been attached to a base which is bonded to the tub.

A practical problem in the manufacture of laundry tubs of the type described has been to provide a construction which can be economically packed and shipped. In order to reduce shipping costs, it has been conventional to nest several tubs, one within another in a single carton. The supporting legs and/or metal bases were packed separately, since there was no practical way of including the structure in the tub carton without scratching and damaging the tubs. When the tubs were sold in a store, the seller would unpack the separate cartons and usually place the legs and base within each tub. This practice also resulted in scratching and marring of the tubs.

Summary of the invention

The new tub which forms a part of the present invention is a relatively inexpensive molded construction which has a back drain and is formed so that it can be firmly supported by legs without the need of bolts, nuts, adhesives, or other fastening means. More particularly, the tub includes an integrally molded base having leg pockets adapted to receive the upper ends of supporting legs. The formation of the leg pockets is such that the ends of metal legs can be simply inserted and locked in place to provide a rigid and sturdy tub assembly.

As will hereinafter be described in greater detail, the new tub construction results in an important reduction in packaging and shipping costs. The new construction is such that the legs can be conveniently packaged within the integrally molded base against the bottom of the tub and four or more tubs nested in a single carton. Thus, the separate carton heretofore used for the bases and legs is eliminated. The tubs can be unpacked from the carton as needed and handled by the purchaser with the

2

legs still held in place. This eliminates damage to the tub during both shipment and when the tub is sold.

Additional features and a fuller understanding of the invention will be had from the following detailed description and the accompanying drawings.

Description of the drawings

FIGURE 1 is a top plan view of the preferred tub construction comprising one aspect of this invention;

FIGURE 2 is a cross-sectional view taken on the line 2—2 of FIG. 1;

FIGURE 3 is a rear elevational view of the tub construction shown in FIG. 1;

FIGURE 4 is a bottom plan view of the tub construction shown in FIG. 1;

FIGURE 5 is a fragmentary cross-sectional view taken on the line 5—5 of FIG. 4;

FIGURE 6 is a fragmentary cross-sectional view taken on the line 6—6 of FIG. 4;

FIGURE 7 is a view similar to FIG. 4 and shows the tub packed with cooperating legs for shipment;

FIGURE 8 is a vertical cross-sectional view of a plurality of tub and leg assemblies packed for shipment; and

FIGURE 9 is a partially exploded perspective view of a double tub assembly.

Referring now to the drawings, and to FIGS. 1-6 in particular, the preferred tub construction of the invention is indicated by reference numeral 20. As generally described above, the tube 20 is preferably made of a suitable injection moldable plastic such as polypropylene or the like, although, it is to be understood that the invention is not limited to any particular material or, in its broader aspects, to an injection molded construction. However, such a construction is advantageous, since the tub can be molded with relatively thin walls on the order of one-eighth of an inch in thickness while still retaining the necessary strength and rigidity. In addition to affording a high strength-to-weight ratio which makes it possible to obtain considerable savings in both weight and cost of materials, the preferred tub 20 can be molded automatically, thereby providing a further savings in labor costs.

The illustrated tub 20 includes side walls 21-24 and a bottom wall 25. A rim 26 is formed around the top edges of the walls 21-23 and an integral ledge 27 extends beyond the wall 25 which may be termed a rear wall for purposes of description. As most clearly shown in FIG. 4, the ledge 27 is formed by a "U" or "dog-eared" configuration of the ledge. Spaced apart mold rings 30 also are formed on the underside of the ledge for the purpose of mounting the faucets (not shown). During installation, holes are drilled through the ledge 27 into the rings 30 and the tapped ends of the faucets are inserted through the holes. The faucets are secured to the ledge by placing washers over the tapped ends in engagement with the rings 30 and threading nuts on the tapped ends against the washers.

The underside of the rim 26 is molded with spaced ribs 35 each of which has a generally U-shaped slot 36 (FIG. 5). These rib formations 35 form clips by which a reinforcing rod 37 can be secured to the rim 26 after the tub has been molded. To this end, the slots 36 are preferably formed to have a width slightly less than the diameter of the rod 37. The plastic will deform to permit insertion of the rod into the slots and yet will tightly grip around the rod so that it is immovable, thereby affording a sturdy and rigid assembly. As shown, the rod 37 is U-shaped and extends around the walls 20-23; however, it should be pointed out that it is not necessary for the legs of the rod to be coextensive with the walls 22 and 23.

A drain 40 formed with drain holes 41 is molded in bottom wall 25. The drain 40 is located on the centerline of the tub 20 adjacent the rear wall 24. With this so-called back drain construction, an overflow tube inserted into the drain will be in an out-of-the-way location and will not interfere with convenient overhang of hoses which may extend from an associated washing machine to the overflow tube. The drain 40 is also molded with external threads 42 whereby the drain can be connected to the usual drain casting (not shown) without using the conventional drain plugs and associated structure.

In order to permit a back drain to be used, the tub 20 is molded with an integral base which is formed by a flange 45 that projects from the bottom wall 25. As shown, the base flange 25 extends below the walls 21-23 and terminates below the wall 24, thereby providing ready access to the drain 40. The four corners of the base flange 45 are formed with leg pockets 46. The leg pockets 46 are generally triangular in bottom plan view (FIG. 4) and are each defined by wall 47 that extends diagonally across the corner of the base flange. Preferably, the ends of each wall 47 extend a short distance parallel to the flange 45 so as to form a pair of slots 48 which are at right angles to each other and open into the pocket 46 defined by the base flange and the wall 47.

The underside of the bottom wall 25 is molded with ribs 50 which prevent upwardly bowing of the bottom wall, as would result in improper drainage from the tub 20. The ribs 50 include spaced, parallel members 51 which extend from one corner of the base flange 45 diagonally across the bottom wall of the tub to the opposite corner of the base flange. The members 51 project below the bottom wall of the tub and define a packing space 52 for the tub legs.

Reference is now made to FIGS. 7 and 8 which illustrate the convenient manner in which tubs constructed according to this invention can be packaged for shipment. The four supporting legs 55 for each tub, which may be of generally V-shaped cross-sectional configuration, are nested one within another and are placed in the space 52 between the members 51. A cardboard strip 56 or the like may be placed over the legs and the legs held between the members 51 by tape 57. Cardboard L's 58 also are preferably inserted into each leg pocket 46 so as to project a short distance outwardly of the base flange 45 and walls 47.

Thus assembled, a plurality of the tubs 20 may be nested and packaged with the legs in a single carton. As most clearly shown in FIG. 8, the projecting cardboard L's 58 abut the inner surfaces of the next lower tub to prevent the base flange 45 of the upper tub from engaging and scratching the lower one. When being sold, each tub assembly can be unpacked and conveniently handled by the user with the legs 55 still held in place between the members 51.

The tub 20 and legs 55 are simply assembled during installation by removing the legs from below the tub and inserting each leg into a pocket 46. The legs are locked in the pockets 46 by engaging the sides of the legs in the slots 48. In this manner a rigid tub and leg assembly is effected without using any separate fastener elements. Since the base flange 45, including the pockets 46, is an integral part of the tub, there is no problem of preventing tub rotation and rocking, as has been encountered with conventional rear drain constructions.

FIGURE 9 illustrates the preferred manner of connecting two of the tubs 20 to form a double tub assembly 70 and of mounting four legs 55 to complete the tub assembly. As shown in FIG. 9, the ledge portion 27 of each tub is partially cut off so the remaining shelf portions can be brought into edge abutment. A pair of connecting strips 72 and 73 of metal or the like are provided at the front and at the back of the abutting tubs for connecting the tubs along the adjoining portions of the base flanges 45. Each pair of connecting strips is arranged so that an

outwardly bent end portion 72a of the strip 72 overlies an end portion of the strip 73 and so that the overlapping end portions bridge the space between the tubs. The pairs of strips are secured to the tubs by bolts or other suitable fasteners (not shown) which extend through the base flanges 45. Thus secured, the strips 72 and 73 serve as an effective means for rigidly connecting the tubs 20 in a manner which prevents relative movement. In order to facilitate packing, the lengths of the strips 72 and 73 are such that the strips can be placed within the confines of the single carton for the tubs. This can be accomplished for example, by placing the strips diagonally in the carton.

As described above, the legs 55 are of V-shaped cross-sectional configuration and have upper ends adapted to fit into the pockets 46 with the sides of the legs being received in the slots 48. Because of this construction, each leg can be inserted easily into one of the pockets 46 at the perimeter of the tub assembly and the sides of the legs forced into the slots, whereby the legs are securely locked in their assembled position.

Many other modifications and variations of the invention will be apparent to those skilled in the art in the light of the foregoing detailed disclosure. Therefore, it is to be understood that, within the scope of the appended claims, the invention can be practiced otherwise than as specifically shown and described.

What is claimed is:

1. An assembly of nested tubs, each of said tubs including side walls and a bottom wall, means for packing tub supporting legs on the underside of each tub, said means comprising at least two spaced members extending below said tub bottom walls, and sets of legs adapted to support said tubs when in use, each set of legs extending across the undersurface of a bottom wall of a tub and being held in place between said members.
2. In combination:
  - (a) a plurality of molded plastic tubs nested one within another,
  - (b) each of said tubs including side walls, a bottom wall, leg-securing structure depending from said bottom wall near the corners of said tub, said structure having openings for receiving the ends of tub-supporting legs when the tub is used, and spaced, diagonally extending members molded on the undersurface of said bottom wall, said members cooperating to define means for packing tub-supporting legs,
  - (c) and a plurality of tub-supporting legs held against the undersurface of the bottom wall of each tub,
  - (d) said legs being disposed between said members and extending diagonally across the undersurfaces of said tubs.
3. The combination as claimed in claim 2 wherein said members on each tub extend from one corner of the tub to the opposite corner.
4. The combination as claimed in claim 2 including means engaged between said leg-securing structure of each tub and the bottom wall of the next lower tub for maintaining the bottoms of said tubs out of contact with one another.
5. The combination as claimed in claim 4 wherein said means comprises elements inserted in the openings of said leg-securing structure.
6. An assembly of nested tubs, each of said tubs including side walls, a bottom wall, and leg-securing structure extending from said bottom wall; a plurality of tub-supporting legs held against the undersurface of the bottom wall of each of said tubs; and means extending from the leg-securing structure of said tubs and maintaining the bottom of each tub out of contact with the next lower tub.
7. An assembly of a laundry tub and a plurality of individual supporting legs arranged with said tub for shipment, said tub including side walls and a bottom wall, and means for packing said legs on the underside of said tub, said means comprising at least two spaced members

extending below said bottom wall, said legs extending across the undersurface of said bottom wall and being held in place between said members.

8. An assembly as claimed in claim 7 wherein said members are parallel and extend diagonally on said bottom wall.

9. An assembly of a laundry tub and a plurality of individual supporting legs arranged with said tub for shipment, said tub including side walls, a bottom wall and at least two spaced members projecting from the undersurface of said bottom wall, said legs being disposed between said members and extending diagonally across said bottom wall.

10. An assembly as claimed in claim 9 wherein said members extend diagonally across the undersurface of said bottom wall substantially from one corner of said tub to the opposite corner.

11. An assembly of nested tubs, each of said tubs including side walls, a bottom wall and structure depending from said bottom wall to provide means for packing tub supporting legs, said structure of each tub including spaced rib members extending diagonally on the undersurfaces of said bottom walls, and sets of legs adapted to support said tubs when in use, each set of legs extending diagonally across the undersurface of a bottom wall of a tub and being held in place between said rib members.

12. An assembly of nested tubs as claimed in claim 11 wherein said rib members of each tub extend diagonally

10 across the undersurface of the bottom wall substantially from one corner of the tub to the opposite corner.

13. In combination, a molded plastic tub having a bottom wall, side walls, and means located on the underside of said bottom wall for packing tub-supporting legs in position for shipment, said means comprising at least one member integral with said bottom wall and projecting therebelow, said member extending in a diagonal direction on said bottom wall; and a plurality of tub-supporting legs arranged with said tub for shipment, said legs extending diagonally across the undersurface of said bottom wall in a direction parallel to said member and being held in place adjacent to said member.

14. The combination as claimed in claim 13 wherein said legs are nested one within another.

15. The combination as claimed in claim 13 wherein said member extends substantially from one corner of said tub to a diagonally opposite corner.
